UNITED STATES PATENT OFFICE.

OVERTON WINSTON, OF MINNEAPOLIS, MINNESOTA.

HEADLIGHT.

1,279,203.

Specification of Letters Patent. Patented Sept. 17, 1918.

Application filed April 29, 1916, Serial No. 94,297. Renewed February 15, 1918. Serial No. 217,461.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My invention has for its object to provide an improved headlight especially adapted for use in automobiles, but adapted for more general use, and the invention is directed to improved electro-magnetic means for controlling movements of the lamp socket, whereby the light bulb may be moved toward and from the axis of the reflector.

20 In the accompanying drawings which illustrate the invention, like characters indicate like parts throughout the several views.

Referring to the drawings:

25 Figure 1 is a view partly in side elevation and partly in vertical section illustrating the invention and showing the electric connections in diagram; and

30 Fig. 2 is a view corresponding to Fig. 1, but illustrating a somewhat modified arrangement of the electric connections.

Except for the electrical connections, the construction illustrated in Figs. 1 and 2 are identical and briefly described, are as follows:

35 The numeral 1 indicates the casing of an ordinary headlight, such as generally used in automobiles, and the numerals 2 and 3, respectively, the reflector and glass plate or lens thereof. The electric light bulb 4 is de-
40 tachably mounted in a lamp supporting socket 5, which, so far as the present invention is concerned, may take different forms, but may be assumed to be of the type dis-
closed and claimed in my pending applica-
45 tion 86,851, filed of date, March 27, 1916, and entitled "Headlights". The lamp socket 5 is connected by pivots 6 to a hollow sup-
porting head 7 that has a threaded shank screwed into the hub of an annular anchor-
50 ing plate 8 rigidly secured on the back of the reflector 2 and surrounding an axial passage 2^a thereof. For oscillating the lamp socket, I provide upper and lower electro-magnets 9, both of which are rigidly secured to and

55 carried by horizontally projecting upper and lower plates 10 of the hollow bearing

head 7. At their inner extremities, the electro-magnets are provided with pole pieces 11, and at their outer extremities, with pole pieces 12. The pole pieces 11 act upon and 60 limit the oscillatory movements of the rear end of the lamp socket 5, which latter is of iron or steel and serves as an armature.

Small upper and lower lock levers 13 are intermediately pivoted to the upper and lower 65 plates 10 and are provided at their inner ends with heads that are engageable between the pole pieces 11 and rear end of the armature and are operative to alternately lock the said socket in raised and lowered positions. The extended ends of the lock levers are spring-pressed outward and are of iron or steel so that they serve as armatures that are subject to the outer pole pieces 12 of the co-operating electro-magnets. 75

Referring now to the electrical connections disclosed in Fig. 1, the numeral 14 indicates a battery, or source of electrical energy. One of the lamp contacts, by a well known means, is grounded through the lamp 80 socket, and the other is connected to a wire or battery lead 15 that extends from one side of the battery 14 and is, of course, insulated from the lamp socket. The lamp socket is, as shown, electrically connected to 85 the inner end terminal of coils of the two electro-magnets 9 and the outer terminals of the coils of the said magnets have independent leads 16, which, as shown, are connected to the other side of the battery 14 by a com- 90 mon wire or lead 17 in which a switch 18 is interposed. Another switch 19 is interposed in the lead 15. The switch 18 may be of any suitable character which is adapted to be set at will, to connect the common lead 17, 95 either to the upper or lower lead 16. Also, the switch 19 should be of such character that it is adapted to be set, at will, either in an open or in a closed position.

From the foregoing, it will be noted that 100 in the arrangement illustrated in Fig. 1, the lamp arranged to be connected, in series, with one or the other of the electro-magnets and that whenever current is sent through the lamp the current must also be sent 105 through one or the other of the electro-magnets. With this arrangement, it is the intention that one or the other of the electro-magnets always be kept energized when the circuit is sent through the lamp, so that it 110 will assist in holding the lamp socket in the adjustment desired.

When the switch 18 is in the position shown in Fig. 1, the lower magnet will be energized and will exert a force on the rear end of the lamp socket, holding the same 5 downward, and at the same time, the upper lock lever 13 will coöperate with the lower magnet and lock the said socket in said position. With this arrangement, however, wherein the electro-magnet remains energized to hold the lamp socket in one or the 10 other position, it is practicable to use very lightly spring-pressed lock levers which may be very easily moved into inoperative positions by the magnetic action of the coöperating outer pole pieces.

Obviously, when the switch 18 is moved upward, so as to connect the upper lead 16 to a common lead 17, the upper electro-magnet will be energized, and the upper lock 20 lever 13 will be first released, and then the said energized electro-magnet will move the rear end of the socket upward and carry the light bulb to a point where its filament will be approximately at the axis of the reflector. 25 When the socket is moved upward, the head of the lower lock lever automatically engages under the same and, conversely, when the socket is moved downward, the head of the upper lock lever automatically engages over 30 the socket.

In the arrangement shown in Fig. 2, the battery or source of electrical energy 14^a is connected to one of the lamp contacts by a lead 15^a, and the other lamp contact is 35 grounded through the lamp socket and connected back to the other side of the battery, through a lead 19. The upper and lower electro-magnets, in this arrangement, are connected in multiple with the lamp, or 40 otherwise stated, are connected across the leads 15^a and 19 by shunt circuits 20 having independently operative switches 21 adapted to be set, either in open or closed positions. The lead 15^a is also preferably provided 45 with a suitable switch 22 which must always be set in a closed position when either the lamp or one or the other of the electro-magnets is connected to the battery circuit, but when the upper switch 21 is closed, the 50 upper electro-magnet will be energized, and when the lower switch 21 is closed, the lower electro-magnet will be energized. With this arrangement, it is, of course, possible to cut out either one or both of the electro-magnets 55 while the current is being supplied to the lamp but also possible to shunt part of the current through one or the other of the electro-magnets all of the time that current is being supplied to the lamp. Both of the 60 arrangements described make it possible to keep one or the other of the electro-magnets energized and operative on the lamp socket all of the time that the current is being supplied to the lamp, and this, as already 65 stated, causes the electro-magnets and lock

levers to coöperate in holding the lamp socket in either set position and against rattling, thereby making possible the use of light and easily actuated lock levers and like devices that do not require large electro-magnets for their operation. Furthermore, the lamp socket is nearly balanced on its pivot and, as it normally has contact with one or the other of the pole pieces 11, very slight magnetic action is required to maintain such contact. The lock levers, however, provide further and more positive means for preventing rattling and for positively locking the socket in the one position or the other. Especially, the said locks are important because they serve to hold the socket locked in the one position or the other and against rattling when the current is cut off from the lamp, and, of course, also from the 75 magnets.

While the switches 21 may be of any suitable character, nevertheless, they would preferably be of a type wherein the one will be opened when the other is closed, so that only one can be closed at a time.

What I claim is:

1. In a headlight, the combination with a reflector, of a lamp socket movable in respect to the axis thereof, opposing electro-magnets for moving said socket from one position to another, a source of electrical energy, circuit connections between said lamp and source of electrical energy, leads for said electro-magnets, and switch mechanism, by which latter, either of 100 said electro-magnets may be continuously energized while current is being delivered to the lamp in said socket, and alternately operative socket locks subject to said electro-magnets and coöperating with said electro-magnets to hold said socket in its different 105 adjustments.

2. In a headlight, the combination with a reflector, of a pivoted lamp socket, upper and lower electro-magnets for moving said socket in different adjustments, a source of electrical energy, circuit connections between said socket, source of electrical energy and said magnets, for connecting the electric light bulb held by said socket in series, with one or the other of said electro-magnets, a switch mechanism whereby either of said electro-magnets may, at will, be connected in circuit with said lamp, and upper and lower lock levers subject to said upper and lower electro-magnets, respectively, and coöperating with said lower and upper electro-magnets, respectively, to hold said lamp socket in one or the other of its 115 adjustments.

3. In a headlight, the combination with a reflector, of a lamp socket movable toward and from the axis of said reflector, upper and lower electro-magnets for moving said socket into different adjustments, 130

a source of electrical energy, certain connections between said socket, source of electrical energy and said magnets, for connecting the electric light bulb held by said 5 socket, in series with one or the other of said electro-magnets, switch mechanism, whereby either of said electro-magnets may, at will, be connected in circuit with said lamp, and magnet released socket locks co- 10 operating with said electro-magnets to hold said socket in the one position or the other

when the lamp circuit is open, and serving, of themselves to hold said socket in the one position or the other when the lamp circuit is closed.

15 In testimony whereof I affix my signature in presence of two witnesses.

OVERTON WINSTON.
